UNITED STATES PATENT OFFICE

98,696

DESIGN FOR A FRUIT HOLDER OR SIMILAR ARTICLE

Walter Rogers, Bay Shore, N. Y.

Application August 27, 1935, Serial No. 58,331

Term of patent 3½ years

To all whom it may concern:

Be it known that I, Walter Rogers, a citizen of the United States, residing at Bay Shore, in the county of Suffolk and State of New York, have invented a new, original, and ornamental Design for a Fruit Holder or Similar Article, of which the following is a specification, reference being had to the accompanying drawing, forming part thereof.

The figure is a perspective view of a fruit holder or similar article, showing my new design.

I claim:—

The ornamental design for a fruit holder or similar article, as shown.

WALTER ROGERS.
